H. J. HIBSCHLE.

ROCK DRILL.

APPLICATION FILED AUG. 10, 1908.

924,350.

Patented June 8, 1909.

UNITED STATES PATENT OFFICE.

HERMAN J. HIBSCHLE, OF VICTOR, COLORADO, ASSIGNOR TO THE MACCORMICK DRILL AND MANUFACTURING COMPANY, INCORPORATED, OF DENVER, COLORADO.

ROCK-DRILL.

No. 924,350.

Specification of Letters Patent.

Patented June 8, 1909.

Application filed August 10, 1908. Serial No. 447,696.

To all whom it may concern:

Be it known that I, HERMAN J. HIBSCHLE, residing at Victor, in the county of Teller and State of Colorado, have invented certain new and useful Improvements in Rock-Drills, of which the following is a specification.

My invention relates to certain new and useful improvements in rock drills, pneumatic hammers and the like, and in its generic nature the invention seeks to provide a drill of an improved type wherein the wearing surface between the hammer piston and the casing may be renewed by the provision of a bushing, insertible in the casing, and around the hammer piston to take the place of the worn parts of the casing.

More subordinately my invention embodies those novel details of construction, combination and arrangement of parts, all of which will be first described in detail, and then be specifically pointed out in the appended claims, reference being had to the accompanying drawings in which:

25 Figure 1 is a side elevation of a part of the rock drill embodying my invention. Fig. 2, is an enlarged central vertical longitudinal section and part elevation, parts being broken away. Fig. 3, is a side elevation of 30 the removable bushing or sleeve. Fig. 4, is an end elevation thereof looking at the smaller end. Fig. 5, is an end elevation of the bushing shown in Fig. 3, looking at the larger end.

35 Referring now to the accompanying drawings in which like letters and numerals of reference indicate like parts in all of the figures, 1 represents the main body portion of the casing which has the front reduced portion 1^a, and which is closed at the opposite end by a back head plug 2 which carries the control valve 5, as indicated in Fig. 1.

The casing 1 is provided with the internal chamber 1^b wherein the hammer piston 3 45 operates. The chamber 1^b has a portion of large bore 1^x and a portion of smaller bore 1^y merging therewith, and at the juncture of the bores 1^x and 1^y the casing is provided with an internal annular groove 1^c which 50 connects with the working agent port 1^d that in turn communicates with the passage 2^e in the back head plug 2 through a radial port or ports 2^d and the annular port 2^e of the

back head plug, as indicated in Fig. 2 of the drawings.

The portion of the internal bore of the body portion of the casing of lesser diameter 1^y is provided with an internal annular groove 1^f that communicates with the exhaust passage 1^g that passes the exhausted working agent to atmosphere, as indicated in Fig. 2.

The front part 1^a of the casing is provided with an internal bore 1^h, in which the hammer head 3^d of the hammer piston 3 operates 65 to impact the striking plug 1^k.

The hammer piston 3 may be provided with packing rings 3^a and is provided with the piston head 3^b which works in the casing chamber 1^x, while the bottom portion proper 70 of the piston 3 works in the reduced bore 1^y of the casing.

The piston 3 is provided with the ports 3^c as indicated, for the passage of the working agent, in a manner which will be readily understood by reference to the drawings.

In order to provide a bearing for the hammer piston 3 within the casing which may be renewed when worn, or in order to provide a bearing to be inserted into drills which have 80 become worn by the reason of the action of the hammer piston 3 on the casing walls, I provide a bushing 4 of a softer material than the piston 3, or the casing 1, preferably, the bushing 4 is made of hard brass when the 85 casing 1 and piston 3 are iron or steel, and in order that the bushing 4 may be held in place within the casing immovable, it is made to fit the two bores 1^x and 1^y of the casing. To this end the bushing 4 is provided with a 90 portion of large diameter 4^a and a portion of smaller diameter 4^b as indicated, the bushing 4 being held in place by the back head plug 2 when screwed home.

Each section 4^a and 4^b of the bushing 4 is provided with a series of circumferentially arranged grating ports 4^c—4^d which register with the annular ports 1^c and 1^f respectively of the casing 1, the ports 4^c and 4^d being in the nature of gratings, that is, of small area 100 so that the packing rings 3^a of the piston 3 will not be scratched as the piston reciprocates within the casing.

In practice the drill may be constructed with the bushing 4 omitted, and when the 105 drill casing and piston wear down so that the

piston works too loosely in the casing 1 the casing may be supplied with a bushing 4 and hence the life of the drill prolonged.

From the foregoing description taken in connection with the accompanying drawings, it is thought the complete construction, operation and advantages of my invention will be readily understood by those skilled in the art to which the invention appertains.

10. What I claim is:

1. A rock drill comprising a hammer casing having an internal chamber and a hammer piston operable therein combined with a removable bushing in position between the hammer piston and the interior wall of the casing said bushing consisting of a tubular member having walls of the same thickness throughout.

2. A rock drill comprising a hammer casing having a main body portion and a front end portion, said body portion having a bore of two diameters, and said front end having a bore merging with that of the body portion, a hammer piston operable within the main body portion bore and having a head shaped to project into the bore of the front end portion of the casing at times, said hammer piston having a solid core portion throughout its length and in alinement with said head, said piston having a series of longitudinal bores surrounding said core and having radial bores registering with said longitudinal bores, said casing having a substantially annular air inlet groove in the portion of greatest bore, means for leading compressed air or working agent into said groove to operate said piston, said casing having a substantially annular exhaust groove in its portion of lesser bore, and having an exhaust passage 40 for leading the exhaust to the atmosphere from said exhaust groove, and a removable bushing interposed between the hammer piston and the casing.

3. A rock drill comprising a hammer casing having a bore, of a plurality of diameters, and a hammer piston operable within said bore combined with a removable bushing

interposed between the hammer piston and the casing said bushing having a plurality of diameters to correspond to those of the hammer casing, the walls of said bushing being of the same thickness throughout.

4. A rock drill comprising a hammer casing having a bore, of a plurality of diameters, a hammer piston operable within said bore combined with a removable bushing interposed between the hammer piston and the casing, said casing bore having a plurality of annular grooves, one in communication with the working agent source of supply and the other in communication with the atmosphere and said bushing having a plurality of grating portions to aline with said grooves.

5. A removable bushing for rock drills and the like comprising a tubular body whose walls are of the same thickness throughout, said tubular body having a plurality of diameters and provided with a plurality of sets of apertures forming grating portions.

6. A bushing for rock drills and the like comprising a tubular body having a series of longitudinally arranged rectangular apertures lying parallel with the axis of the bushing and forming a grating portion.

7. A rock drill comprising a hammer casing having a bore of a plurality of diameters, a hammer piston having a plurality of diameters and operable within said bore, combined with a soft metal removable bushing interposed between the hammer piston and the casing, said bushing having two diameters and formed with its walls of the same thickness throughout, said casing bore having a plurality of annular grooves, one in communication with the working agent source of supply and the other in communication with the atmosphere, the said bushing having grating apertures in alinement with said grooves.

HERMAN J. HIBSCHLE.
